UNITED STATES PATENT OFFICE.

JAMES C. NORDGRAN, OF LOS ANGELES, CALIFORNIA.

DESIGN FOR A DIRECTION SIGNAL AND STOP LIGHT.

Application filed March 8, 1924. Serial No. 8,882. Term of patent 14 years.

To all whom it may concern:

Be it known that I, JAMES C. NORDGRAN, a citizen of the United States, residing at Los Angeles, in the county of Los Angeles and State of California, have invented a new, original, and ornamental Design for Direction Signal and Stop Light, of which the following is a specification, reference being had to the accompanying drawing, forming a part thereof.

In the accompanying drawings Fig. 1 is an elevation of a direction signal and stop light embodying the features of my invention; Fig. 2 is an end elevation thereof.

I claim:

The ornamental design for a direction signal and stop light substantially as shown.

JAMES C. NORDGRAN.
